(57) **CLAIM**

The ornamental design for a cabinet as shown.

DESCRIPTION

FIG. 1 is a front, right, and top perspective view of a cabinet, showing my new design;

FIG. 2 is a rear, left, and bottom elevation view thereof;

FIG. 3 is a front elevation view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of an encircled area labeled "9" in FIG. 3;

FIG. 10 is a front, left, and top perspective view of a second embodiment of the cabinet, showing my new design;

FIG. 11 is a rear, right, and bottom elevation view thereof;

FIG. 12 is a front elevation view thereof;

FIG. 13 is a rear view thereof;

FIG. 14 is a left side elevation view thereof;

FIG. 15 is a right side elevation view thereof;

FIG. 16 is a top plan view thereof;

FIG. 17 is a bottom plan view thereof; and,

FIG. 18 is an enlarged view of an encircled area labeled "18" in FIG. 12.

The broken lines and the shaded areas bounded by broken lines depict portions of the cabinet that form no part of the claimed design. The dot-dash broken lines shown in FIGS. 3, 9, 12, and 18 framing portions of the cabinet for enlargements purposes form no part of the claimed design.

1 Claim, 18 Drawing Sheets
